TICKET HOLDER AND PUNCH

Otto C. Heinemann, Milwaukee, Wis.

Application August 2, 1947, Serial No. 765,725

2 Claims. (Cl. 206—40.6)

1

The invention relates to ticket punches and more particularly to punches for punching tickets used in restaurants and lunch rooms to show the amounts due from the customer.

In the usual ticket punches, the tickets are bound together by wiring the stub portions of the tickets together, and in using the punch the ticket has to be torn off of the stub before punching it. Frequently, where the operator is in a hurry portions of the ticket itself are torn off in removing it from the stub so that the ticket has to be thrown away. One object of this invention is to provide a ticket punch in which the tickets do not have stubs and are not wired together but are separate and stacked in a container forming the handle of the punch from which they are readily withdrawn as needed, thus eliminating the cost of wiring the tickets together, the extra paper forming the stub, and the wastage of tickets in being torn while removing them from the stub which are items of considerable expense.

A further object of the invention is to provide a ticket punching mechanism so constructed and arranged that the clippings from the punching operation are received within the punch, thus preventing the clippings from falling into food, or on tables or on the floor as occurs with the usual punches.

The invention further consists in the several features hereinafter set forth and more particularly defined by claims at the conclusion hereof.

In the drawings:

Fig. 1 is a plan view of a ticket punch embodying the invention;

Fig. 2 is a side elevation view of the punch;

Fig. 3 is a vertical sectional view taken on the line 3—3 of Fig. 1;

Fig. 4 is an exploded perspective view of the punching mechanism;

Fig. 5 is a view similar to Fig. 4 showing certain modifications;

Fig. 6 is a vertical sectional view taken on the line 6—6 of Fig. 2;

Fig. 7 is a vertical sectional view taken on the line 7—7 of Fig. 2.

Referring to the drawings, the numeral 8 designates generally a sheet metal casing having a bottom wall 9, side walls 10, front wall 11, and back wall 12.

A cover member 13 having side walls 14 is hingedly secured at 15 to the top of the back wall 12 and has yieldable extensions 16 which have punched in projections 17 to engage in recesses or holes 18 in the side walls 10 to hold

2

said cover in a closed position. The casing 8 with its cover 13 thus forms a container for receiving a stack of separate stubless tickets 19 which are yieldingly urged upwardly toward the cover by the wings of a flat leaf spring 20 secured intermediate its ends by a rivet 21 to the bottom wall of the casing. Thus by providing a container for receiving separate tickets the usual wired stub tickets with their extra cost and wastage previously referred to are eliminated. It will be noted that the cover 13 is of less length than the length of the tickets, so that the tickets are readily removable, one at a time, from the opening 22 thus provided.

The ticket container formed as above described forms the handle for the punch, and while any suitable punching mechanism may be mounted on the casing at one end of this container, I prefer to use the novel punching mechanism herein shown and which includes a die member 23 and a punch 24 movable relative to each other so as to punch out a V-shaped notch 53 from the sides or ends of the tickets 19.

Referring to Figs. 3, 4, and 6, a U-shaped or channelled sheet metal member 25 is mounted to fit in the forward end of the casing 8 with its side flanges 26 abutting the sides 10 of the casing and its web 27 secured to the bottom of said casing by rivets 28. Part of the web 27 is formed as a tongue 29 bent up to form a centering support for a coiled spring 30. The back edges 31 of the flanges 26 form stops for the forward ends of the tickets 19. The front edge 32 of said flanges is disposed in a vertical plane aligned with the squared front edges 33 of the side walls of the casing from which the edges 34 of said side walls incline downwardly to the top of the front wall 11 of the casing. The top edge portions 35 of the flanges 26 are inclined downwardly toward the front of the casing, to form stop shoulders limiting the downward swinging movement of the punch 24.

The punch 24 includes a hardened steel knife 36 whose shank abuts a spacer block 37 which with the knife is secured to a main shank or operating member 38 by rivets 39.

The operating member 38 is of sheet metal formed to provide front pivot mountings or eyes 40, a knife abutment 41, and side flanges 42 provided with ears 43 having aligned openings 44 which in assembled position align with openings 45 and 46 in the side walls of the casing and the flanges 26 of the member 25 to receive pivot pins 47 whereby the back end of the punch or knife member is pivotally mounted in the casing 8, so

that it may be swung downwardly, by pressure of the operator's thumb upon the member 38, from the position shown in Fig. 2 to a position in which the flanges 42 abut the inclined edges 33 of the member 25.

The die member 23 is a hardened sheet metal plate having a notch 48 therein through which V-shaped knife 36 is adapted to pass with a shearing cut upon the ticket placed between said knife and die. The edge of the member 23 in which the notch is formed is provided with pivot mountings or eyes 49 alineable with the eyes 40 to receive a pivot pin 50. The front end of plate 23 is provided with a rearwardly projecting hook 51 which is slidably mounted in a slot 52 in the front wall 11 and with the pins 47 and 50 holds the punch parts in assembled relation with the casing 8.

The spring 30 mounted on the tongue 29 bears against the underside of the knife or punch member and normally acts to swing this member relative to the die member 23 to a position in which the knife 36 is above the notch 48 as shown in Fig. 3. With the parts in this position, the operator while holding the handle portion of the casing with one hand inserts a side edge of a ticket 19 to be punched between the opened punch parts, and then with the thumb of the hand holding the punch, presses down on the member 38 with the result that the knife 36 is swung downwardly into the notch 48 and in doing so cuts a V-shaped notch 53 in the ticket at the selected valuation number appearing on said ticket, this downward movement of the knife also causing a forward sliding movement of the die member 23 relative to the casing. The clipped portion of the ticket 19 on its severance from the ticket drops down into the compartment 54 provided by the casing at its forward end, so that clippings are prevented from falling into food or onto tables or floors of the restaurant.

In Fig. 5 I have shown a modification of the knife or punch member in which the knife 55 is formed integral with a sheet metal plate 56 having pivot eyes 57 formed therein, which plate together with a spacer plate 58 is riveted to another plate member 59 by rivets 60 which last named plate has flanged sides 61 having ears 62 provided with openings 63 which as in the first described construction aline with the openings 45 and 64 in the side walls of the casing and the member 25, respectively, to receive the pivot pins 47. This knife structure when connected by the pivot pin 50 passing through the eyes 57

and the eyes 49 of the die member 23 functions in the same manner as the first described knife member to sever a notch from the ticket. The first described knife member is preferred as it does not require the use of as much hardened steel as is required by the plate 56.

I desire it to be understood that this invention is not to be limited to any particular form or arrangement of parts except in so far as such limitations are included in the claims.

What I claim as my invention is:

1. In a ticket punch of the character described, the combination of an elongated container forming the handle of the punch and adapted to hold a series of separate stubless tickets, said container having one end enclosing the tickets and a top dispensing opening and holding the tickets in a stack from which they may be removed one at a time through said opening for punching, the punch being mounted in the opposite end of the container and having a part forming a stop adjacent said opening to limit the endwise movement of said tickets in said container.
2. The structure as defined in claim 1 in which the punch comprises a die member and a punch member normally forming a portion of the top of the container and pivotally connected together intermediate the ends of said top, said die member having an opening therethrough for receiving the punch and being mounted for swinging and sliding movement on the front end of said container, said punch member pivotally supported on the sides of said container, means for biasing said die and punch members to a normal ticket receiving position, said members being operable to punch the ticket by pressure exerted on the top of one of said members.

OTTO C. HEINEMANN.
